(52) **U.S. Cl.**

The ornamental design for a magnetic therapy apparatus, as shown and described.

USPC **D23/207; D24/188**

DESCRIPTION

(58) **Field of Classification Search**

1. Magnetic therapy apparatus

USPC D24/188; D11/90, 131, 86, 89; D21/714

1.1: Front

CPC C02F 1/48; C02F 1/481; C02F 1/482

1.2: Back

See application file for complete search history.

1.3: Top

USPC D23/207; D24/188

1.4: Bottom

USPC D24/188; D11/90, 131, 86, 89; D21/714

1.5: Left

CPC C02F 1/48; C02F 1/481; C02F 1/482

1.6: Right

See application file for complete search history.

1.7: Cross sectional

USPC D23/207; D24/188

1.8: Cross sectional

USPC D23/207; D24/188

The present article includes a spherical exterior case with permanent magnets placed in the exterior case; the exterior case has pentagonal and hexagonal cut faces formed on its surface; fig. 1.7 is a cross-sectional view taken along the A-A line shown in the fig. 1.3; fig. 1.8 is a cross-sectional

(Continued)

view showing a transparent portion with cross sectional lines where the cross-hatch lines indicate portions of the drawings which are transparent.

1 Claim, 8 Drawing Sheets
